GOLF PUTTER HEAD

George Adrian Phillips, Cudahy, Wis.

Application January 12, 1959, Serial No. 54,136

Term of patent 14 years

(Cl. D34—5)

Figure 1 is a perspective view of the golf putter head from the left front corner thereof;

Figure 2 is a front elevation;

Figure 3 is an elevation taken from the rear of the golf putter head;

Figure 4 is a top plan view;

Figure 5 is a side elevation showing the hosel rounded side;

Figure 6 is a cross-section of the hosel on the line 6-6 of Figure 5; and

Figure 7 is a cross-section on the line 7-7 of Figure 5.

I claim:

The ornamental design for a golf putter head, as shown.
